US00D940548S

(12) **United States Design Patent** (10) Patent No.: **US D940,548 S**
(45) Date of Patent: **** Jan. 11, 2022**

(54) **CAPSULE**

- (71) Applicant: **GCS German Capsule Solution GmbH**, Bergisch Gladbach (DE)
(72) Inventor: **Marc Krüger**, Bergisch Gladbach (DE)
(**) Term: **15 Years**
(21) Appl. No.: **35/510,939**
(22) Filed: **Jun. 10, 2020**

(80) **Hague Agreement Data**

- Int. Filing Date: **Jun. 10, 2020**
Int. Reg. No.: **DM/208849**
Int. Reg. Date: **Jun. 10, 2020**
Int. Reg. Pub. Date: **Dec. 11, 2020**
(51) LOC (13) Cl. 09-03
(52) U.S. Cl.
USPC **D9/416; D9/428**
(58) **Field of Classification Search**
USPC D9/416, 429, 428, 424, 500, 503;
D7/398, 397, 400, 399, 387
CPC B65D 85/804; B65D 85/8043; B65D
85/8046
